(57) **CLAIM**

The ornamental design for a massage machine, as shown and described.

DESCRIPTION

FIG. 1 is a front perspective view of a first embodiment of the massage machine.

FIG. 2 is a top view of the first embodiment of the massage machine.

FIG. 3 is a front view of the first embodiment of the massage machine.

FIG. 4 is a right side view of the first embodiment of the massage machine, the left side view being a mirror image thereof.

FIG. 5 is a rear view of the first embodiment of the massage machine; and,

FIG. 6 is a top view of a second embodiment of the massage machine.

The bottom view of the massage machine is plain and unornamented.
